UNITED STATES PATENT OFFICE.

CHARLES VOGEL, OF FORT LEE, NEW JERSEY.

COMBINED DOOR-CHECK AND ALARM.

SPECIFICATION forming part of Letters Patent No. 337,538, dated March 9, 1886.

Application filed July 13, 1885. Serial No. 171,421. (No model.)

To all whom it may concern:

Be it known that I, CHARLES VOGEL, of Fort Lee, in the county of Bergen and State of New Jersey, have invented an Improvement 5 in Door-Stops, of which the following is a specification.

With doors that are closed by a spring considerable noise often arises from the slamming of the door, and when the spring is made 10 weaker the door is likely to partially open by the action of the wind.

My present improvement is made for accomplishing the twofold object of preventing the door slamming and of holding the same with 15 a sufficient force to keep the same in a position to which it may be moved.

In the drawings, Figure 1 is an elevation of the holder and the spring with which it is connected. Fig. 2 is a plan of the same. Fig. 3 20 is a separate view of the rubber roller and the stop that acts upon the same. Fig. 4 is a cross-section of the bolt that supports the elastic roller, and Fig. 5 is a sectional view of the latch for operating the gong.

25 A portion of the door is shown at A, and B represents a portion of the frame.

The hinges of the door may be of any desired character; also, the spring employed to close the door may be of ordinary construction. I however have shown the case C, from which an arm, D, extends, and the same forms one part of the stop. I have shown a link, d', pivoted at the end of the arm D and connecting the same to the plate d² upon the 30 door, so that when the door A is opened the stop-arm D will be swung back, and in so doing the spring within the case C will be strained; but I do not limit myself to any particular kind of spring. The stop-arm D is 35 made with an arch, D', and a finger, D², the diameter being slightly less than the diameter of the stop-roller E, that is supported by a bracket-plate, F, and stud-bolt f, which plate, by preference, is fastened to the door-frame; 40 but the position of the parts might be reversed, so that the stop-roller E would be upon the door and the arch D' and finger D² upon the door-frame. This stop-roller E is elastic, and as the stop-finger D² presses against the 45 side of the same as the door swings the said finger D² compresses the roller as the roller turns upon its axis, thereby gradually stop-

ping the momentum of the door, until finally the stop-arm and stop-roller are brought sufficiently close together for the roller at one 55 side to coincide, or nearly so, with the bottom of the arch D', thus forming a perfect elastic stop that prevents the door slamming, and the finger D², acting against one side of the elastic stop-roller E, holds the door from moving 60 by any slight pressure, such as that resulting from any currents of air; but such finger D² releases its hold upon the elastic stop-roller E as soon as sufficient force is applied to separate the stop-arm from the stop-roller. It is usually preferable to slot the bracket-plate F 65 where the stud-bolt f passes through the same, and to make use of washers, so that the axis or stud-bolt f of the stop-roller E may be adjusted to occupy the proper position relatively 70 to the stop-arch D' and stop-finger D², and the bolt f, that forms the axle for the roller, is square where it passes through the slot of the bracket; but the center of this square is not in line with the center of the axle, so that by 75 changing position of the square in the slot the axle of the roller will cause the roller to press more or less firmly against the finger D².

It is convenient to combine along with the door-spring and door-stop an alarm-bell, so 80 that the bell will be rung when the door is opened. To effect this object I support the gong-bell K upon a stud, k, projecting from the arm D, and the hammer L is upon a spring-arm, l, that passes out from the stock l², that 85 is pivoted at I to the back of the finger D², and there is a spring, S, to swing the hammer upon its pivot I.

Upon the bracket-plate F is an arm, T, to which is pivoted the latch u, and there is a 90 turning plate, v, which, when swung up against the end of the latch u, swings the said latch u out of the path of the stock of the hammer L; but when this plate v is turned aside the spring v' of the latch u throws the end of such latch into the path of the stock l², so that said latch u holds back the hammer-stock and hammer while the stop-arm D is swung in opening the door, and the spring S projects the hammer, striking the bell or gong K, as soon as the 95 stock l² swings clear of the spring latch u striking the gong.

I claim as my invention—

1. The combination, with the elastic stop-

roller E, of the stop-arm D, having the arch D' and finger D² to act in connection with the said roller E in stopping and holding the door, substantially as set forth.

- 5 2. The combination, in a door-stop, of an elastic roller, E, a bracket-plate, F, an adjustable stud-bolt, f, for supporting said roller, the arch D', and its finger D², substantially as set forth.
3. The combination, with the stop-arm D, having arch D', link d', door-plate d², elastic stop-roller E, and stop-finger D², of the gong

K, supported by a stud on the stop-arm D, the hammer L, the stock l² for the same, pivoted at I, the spring S, latch u, and turning plate v 15 upon the bracket of the stop-roller E, substantially as set forth.

Signed by me this 7th day of July, A. D. 1885.

CHARLES VOGEL.
